UNITED STATES PATENT OFFICE.

FREDERIC C. MORTON, OF NEW HAVEN, CONNECTICUT, ASSIGNOR TO THE ANSONIA
O & C CO., OF ANSONIA, CONNECTICUT, A CORPORATION.

ARMBAND CLASP.

Application filed March 10, 1922. Serial No. 542,628.

To all whom it may concern:

Be it known that I, FREDERIC C. MORTON, a citizen of the United States, residing at New Haven, in the county of New Haven 5 and State of Connecticut, have invented a new and useful Improvement in Armband Clasps; and I do hereby declare the following, when taken in connection with the accompanying drawings and the characters of 10 reference marked thereon, to be a full, clear, and exact description of the same, and which said drawings constitute part of this application, and represent, in—

Fig. 1 A perspective view of an arm-band 15 provided with one form which my improved clasp may assume.

Fig. 2 An enlarged, broken, sectional view thereof on the line 2—2 of Fig. 1.

Fig. 3 An enlarged view thereof in trans- 20 verse section on the line 3—3 of Fig. 1.

Fig. 4 A detached perspective view of the clasp, after it has been given its final form.

Fig. 5 A similar view of the clasp in its initial form.

Fig. 6 A view of one of the modified forms which the clasp may assume.

My invention relates to an improvement in arm-band clasps, such as are employed for binding the bows of arm-bands over the 30 joints created by uniting the ends of the elastic webbing thereof, the object being to produce an efficient and ornamental clasp constructed with especial reference to engaging the material so as to hold it against dis- 35 placement, and to avoiding the buckling of the metal when the clasp is bent into its final form, and particularly the cracking or flaking of the enamel or other finish of the metal, if any superficial finish is employed.

With these ends in view, my invention consists in an arm-band clasp having the edges of its face-portion formed with localized inwardly-turned flanges for the indentation 40 and gripping of the fabric, these ears being confined to those portions of the clasp which are not bent in clasping the same upon the band.

My invention further consists in an arm-band clasp having certain details of construction as will be hereinafter described and pointed out in the claim.

In carrying out my invention, I form

localized inwardly-turned gripping-flanges 10 upon the opposite edges of the central portion or face 11 of the clasp, which is produced from a single piece of metal, and the ends 12 of which are made long enough to be folded under the face 11 of the clasp in a plane substantially parallel therewith, and so as to nearly meet. It will be observed, by 55 reference to Figs. 4 and 5 in particular, that the bending of the clasp from its initial U-shaped form, as shown by Fig. 5, to its final flattened tubular form, as shown by the preceding figures, imposes no strain upon the 60 inwardly-turned flanges 10, which are localized, so to speak, and thus rendered immune from bending strains, whereas, when the edges of the clasps are flanged from end to end, which is the common practice, they will 65 buckle and crimp, and if enameled or finished, the same will be flaked off or checked and disfigured.

When my improved band is applied over the bow 13, which in turn is applied over the 70 elastic webbing 14 at the joint 15 thereof, the flanges 10 sufficiently embed themselves in the fabric of the bow, as shown in Fig. 2, to hold the clasp against lateral displacement with respect to the bow and webbing. The 75 bow is thus held in place over the joint of the webbing, and the joint thereof concealed and protected. In addition to these functions, the clasp provides an attractive finish 80 for the arm-band.

In the modified construction, shown by Fig. 6, the clasp 15 is made on the same principle as that already described, but given a cylindrical rather than a flattened tubular form, the retaining-ears 16 being, in this instance, so short as not to be bent or disturbed appreciably when the clasp is bent 85 into its final form in being applied to an arm-band.

I claim:

As a new article of manufacture, a clasp for finishing arm-bands, consisting of a narrow strip of flat sheet-metal shaped to form a central face-portion and two complementary integral retaining-arms extending 100 therefrom, the said face-portion being formed upon its edges and between the said arms with localized, inwardly-turned retaining-fingers adapted in length and posi-

tion to escape bending when the said arms are clasped upon the arm-band, whereby the finish upon the face-portion and flanges of the clasp is not disturbed and mutilated when the arms receive their final bending in applying the clasp to an arm-band.

In testimony whereof, I have signed this

specification in the presence of two subscribing witnesses.

FREDERIC C. MORTON.

Witnesses:

FREDERIC C. EARLE,
MALCOLM P. NICHOLS.
